O. O. REISER

CONTAINER

Filed June 16, 1924

Oliver O. Reiser
INVENTOR:

UNITED STATES PATENT OFFICE.

OLIVER O. REISER, OF FOREST PARK, ILLINOIS, ASSIGNOR TO THE RICHARDSON COMPANY, OF LOCKLAND, OHIO, A CORPORATION OF OHIO.

CONTAINER.

Application filed June 16, 1924. Serial No. 720,201.

To all whom it may concern:

Be it known that I, OLIVER O. REISER, a citizen of the United States, and a resident of Forest Park, in the county of Cook and State of Illinois, have invented certain new and useful Improvements in Containers, of which the following is a full, clear, and exact description, reference being had to the accompanying drawing, forming part of this 10 specification.

My invention relates to battery boxes designed to hold the cells of a storage battery and it has particular reference to such containers as are employed for holding the storage batteries for automobiles.

The object of the invention is to provide a container for this purpose molded or formed integrally from a single piece of suitable material in which the box is so constructed that the liability of fracture or pulling apart of the sides of the box from the cover thereof in lifting or handling the box, is reduced to a minimum.

In the past considerable difficulty has been experienced in the durability of such integral structures for the reason that when lifted by the usual handles there is a tendency to exert an endwise strain on the sides and the weight of the battery cells has tended to crank the side walls and the sealing compound with which the top is held in place, and to open up vents in the container through which the electrolyte escapes.

It is to avoid this difficulty and to provide a construction of handle whereby in lifting and moving the box from place to place the act of grasping the handles will tend to press the sides of the box towards each other instead of subjecting them to an outward strain, to which my invention is directed.

In the drawing:

Figure 1 is a perspective view of the container.

Figure 2 is a vertical section of one end taken on the lines 2-2 of Figure 1.

The box preferably as I have said of a single integral structure, is formed with side walls 1, 2, and end walls 3, 4, bottom 5 and

partitions 6, 7, in the present instance illustrating a three cell battery container with ribs 8, 8, projecting upward from the bottom of the box to sustain the plates of the battery. The end walls 3, 4, are formed preferably somewhat thicker near the upper edge at 12 to reinforce the handles 9, 10, which extend upwardly above the container walls and the end walls and the handle portions are grooved out at 13 to lighten the end walls and by the ribbed structure to give additional strength as the corners of the box are subjected to the most strains. This grooving out the middle portion of the end walls, leaves an angular depression 14 for the handle portions and a horizontal under cut ledge 15 which presents a very effective finger hold in lifting the box.

There is no hole for the hands in lifting the box, so that it cannot be lifted by one hand nor can any outward strain be applied to the end walls. To properly lift the box the user must press inwardly as the handles are employed and the strain both on the projecting handle and the end walls is very largely avoided.

While I have applied my invention to an integrally formed container of the ordinary shape, I do not wish to be limited to either the particular form shown or to an integrally formed box, as many different shapes may be utilized and the construction of handles while preferably for an integral structure will also be found of value for a container with the walls and partitions not integral.

Having thus described my invention, what I claim as new and desire to secure by Letters Patent, is:—

1. A container with side, end and bottom walls with handles secured to the top of the end walls projecting upwardly in the plane of the end walls, said handles being solid and provided with an external under-cut ledge to compel inward pressure as the box is lifted.

2. A container formed in one integral piece with handles projecting upwardly and integral with the end walls, the handles be-

ing solid and provided with an external under-cut ledge to permit grasp of the handles and compel inward pressure as the box is lifted.

5 3: A container formed in one integral piece with handles projecting upwardly and integral with the end walls, with the end

wall reinforced along the upper edge, the handles being solid, and of the thickness of the reinforced portion, and provided with an 10 external under-cut ledge to permit grasp of the handles and compel inward pressure as the box is lifted.

OLIVER O. REISER.
